UNITED STATES PATENT OFFICE.

ALBERT FRENCH, OF BROOKLYN, NEW YORK.

COMBUSTION PROMOTION.

Application filed November 23, 1923. Serial No. 676,486.

To all whom it may concern:

Be it known that I, ALBERT FRENCH, a citizen of the United States, and a resident of Brooklyn, Kings County, and State of New York, have invented certain new and useful Improvements in Combustion Promotion, of which the following is a specification.

The objects of this invention are to promote combustion of fuel in boilers and furnaces and to provide effective means for this purpose which can be readily applied and adapted to existing fuel burning systems.

In the accompanying drawings forming part of this specification, one practical embodiment of the invention is illustrated in different adaptations to a furnace, and it is to be further understood that the invention may be applied and used in other different ways and in other various forms without departure from the true spirit and scope of the invention as hereinafter defined and claimed.

Figure 1 is a broken perspective view showing the invention applied to a conventional type of coal burning furnace.

Figure 2 is a vertical sectional view of the preheater intake which feeds oxygen into the top of the combustion chamber.

Figure 3 is a cross sectional view of the same as taken on substantially the plane of line 3—3 of Figure 2.

Figure 4 is a broken plan view of this preheater installation.

Figure 5 is a detached perspective view of the combined intake and air preheating device.

Figure 6 is a longitudinal sectional view of the preheater chamber.

Figures 7 and 8 are plan and sectional views respectively of the device for spraying preheated air into the front of the combustion chamber.

One special feature of the invention consists in injecting preheated air both into the back and the front of the combustion space in such a way as to agitate and break up the gases of combustion so as to cause carbon monoxide or unconsumed gases to combine more fully and completely with the auxiliary supply of oxygen thus furnished. In the illustration this is effected by means of an injector preheater operating in conjunction with the stack or smoke pipe to supply heated air into the top or back portion of the combustion chamber and another injector

preheater applied to the furnace door for supplying heated air into the front of the combustion chamber.

The first injector is shown in the form of a relatively flat hollow shoe or chamber 10 having an air inlet 11 in its rear wall and an inclined front wall 12 which is faced to the interior of the furnace and provided with air spraying nozzles 13. These nozzles are shown in Figure 6 as tapered toward their discharge ends and provided with flared or cupped outlets 14 and for convenience of manufacture the front wall is shown constructed as a separately formed plate set into an appropriate seat provided in the body of the chamber. The body part of the chamber is shown in the form of a single casting having a dependent lug 15 at the rear for supporting the device on a downward, forward incline and as having a rounded under-surface to enable it to seat closely in the bottom of the flue when used directly in the flue as indicated in Figures 2 and 3.

To prevent a too rapid inrush of air and give time for the air to become properly heated before admission to the exhaust gases, a baffle wall 16 is shown provided directly opposite the inlet 11 and this baffle is furthermore shown as forming one of the walls of a triangular vertical passage through the preheater body, the other two walls 17 of this passage converging toward the front and the sides of the chamber being indicated as constricted toward these convergent walls at 18 to provide convergent channels 19 which direct the incoming air in two convergent streams toward the nozzles. The top of the chamber is shown as inclined downwardly toward the front and the effect as a whole is that the induced air as it is heated and expands is projected by the nozzles as a forceful spray.

The intake for the air is shown in the form of a head 20 covered by a rotatable valve which can be turned to regulate the volume of admitted air. This head is connected with the preheater by suitable piping 21 which is usually extended through the smoke pipe 22 of the furnace.

This fresh air intake may be located within the furnace room or in case of a lack of oxygen may be located in the open air. In the construction illustrated the intake is shown located directly below a chamber or enlargement 23 interposed as a

section of the smoke pipe. This chamber is made of sufficient size to receive the pre-heater without diminishing the cross sectional area of the flue so that the preheater 5 may be installed therein as shown in Figures 2 and 3 without retarding the flow of smoke or furnace gases.

In Figure 1 the preheater is shown as located directly within the furnace structure, it only being necessary in such a case to provide an extended section of the piping 21 by which the preheater is connected with the air intake outside the furnace. The provision of the air inlet in the back of the 15 preheater thus allows for the installation of the preheater either in the furnace or within the smoke pipe chamber and enables the air intake to be disposed either at the bottom, where shown, or at either 20 side or even at the top of the smoke pipe, as conditions may require.

The preheater section of the smoke pipe is shown in Figures 2, 3 and 4 as made in the form of two complementary castings 24, 25, having interfitting tongue and groove joints 26 and secured together by bolts 27. These complementary parts are shown as having necks 28 at their opposite ends reduced to the size of the smoke pipe and in order that these may be readily fitted to such piping, either one or both of them may have attached a collar 29 of sheet metal which can be expanded or reduced more or less to adapt it to variations in 35 size of the flue. This construction, it will be seen, enables the device to be readily interposed in the usual line of smoke pipe.

The draught through the smoke pipe is shown as controlled by a pivoted damper 40 journaled in the pipe in rear of the pre-heater and adapted to be positioned by a handle 31. This damper differs from the ordinary in that it is provided on the face toward the preheater with a concavely 45 curved deflector 32 to turn the gases downwardly and back toward the preheater and thus create more or less of an eddy flow back over the top of the preheater. This damper also is shown as placed quite close 50 to the end of the enlarged section of the pipe and so that when nearly closed as in Figure 2 it will substantially line up with the downwardly inclined breast of the upper pipe section 24.

55 The front preheater is shown in Figures 7 and 8 as consisting of a hollow casting 33 closed by a cap 34 having a dependent hollow projection 35 which forms a substantially U-shaped channel 36 for the flow of 60 gases from the rear to the front of the device. At the front the body casting is shown formed with a series of substantially radially disposed tapered nozzles 37, like those on the other injector provided 65 with flared mouths 38. This air spraying

device is shown supported against the inside of the furnace door 39 by a nipple 40 which screws into the inlet 41 in the back wall of the device and has screwed on its outer end, at the outside of the door, a bell shaped intake 42 which can be regulated by a rotary valve 43.

In Figure 1 two of the door carried pre-heaters are shown and it will be understood that one or a number of them may be used, 75 depending upon the size of the furnace and other conditions and they may be applied to the furnace door or to any other suitable support above the fuel bed. The U-shaped passage 36 provides sufficient area 80 and retards the incoming air enough to insure proper heating of the same before it is sprayed out over the fuel bed and the heating effect may be enhanced by providing heat absorbing fins or ribs on the body 85 of the device which is exposed to the fire, as indicated at 44.

This invention, it will be seen, provides for the admission of regulatable supplies of preheated air to the fuel bed from substantially opposite directions and thereby produces an intimate mixing and more complete combustion of gases. The independent adjustment of the two supplies of air enables securing the best results under widely different conditions of installation. The devices which go to form the several parts of the invention are simple, relatively inexpensive and can be readily installed in the usual furnace equipment.

What I claim is:

1. In a device of the character disclosed, an air preheating chamber adapted for mounting within a horizontal smoke pipe or furnace structure and having a base for supporting the same in such location tilted downwardly and forwardly toward or into the furnace, said chamber having a downwardly inclined front wall faced toward the furnace structure and provided with discharge nozzles extending obliquely of said inclined wall and substantially horizontally in said supported position of the preheater, said preheater further having a pipe inlet in the rear wall of the same and by which an air inlet pipe may be entered from below or above and at various angles.

2. In a device of the character disclosed, an air preheating chamber provided with a pipe inlet in the rear wall of the same and a downwardly and forwardly inclined front wall with obliquely extending air discharge nozzles, said preheater having a base for supporting the same within a substantially horizontal smoke or furnace flue with said oblique nozzles in the inclined front wall discharging substantially horizontally into the bottom portion of the flue and so below the main flow of hot furnace gases through the flue.

3. In a device of the character disclosed, an air preheating chamber provided with a pipe inlet in the rear wall of the same and a downwardly and forwardly inclined front wall with obliquely extending air discharge nozzles, said preheater having a base for supporting the same within a substantially horizontal smoke or furnace flue with said oblique nozzles in the inclined front

wall discharging substantially horizontally ¹⁰ into the bottom portion of the flue and so below the main flow of hot furnace gases through the flue, the sides of said preheater chamber being constructed in rear of the inclined front wall. ¹⁵

In witness whereof, I have hereunto set my hand this 14th day of November, 1923.

ALBERT FRENCH.
